Patented Dec. 22, 1914.

UNITED STATES PATENT OFFICE.

ALBERT H. CARNES, OF ST. LOUIS, MISSOURI, ASSIGNOR OF ONE-HALF TO HURLEY M. TAYLOR, OF ST. LOUIS, MISSOURI.

TRACK-SANDING APPARATUS.

1,121,710.

Specification of Letters Patent.

Patented Dec. 22, 1914.

Application filed October 12, 1914. Serial No. 866,301.

To all whom it may concern:

Be it known that I, ALBERT H. CARNES, a citizen of the United States, residing at the city of St. Louis, State of Missouri, have invented certain new and useful Improvements in Track-Sanding Apparatus, of which the following is a specification, reference being had to the accompanying drawings, forming a part thereof.

10 This invention relates to certain new and useful improvements in track-sanding apparatus.

In track-sanding apparatus, it is, for many reasons, most important that sand 15 from the sand-box or hopper reach the rails quickly when and as required. Hence it is necessary that the sand-supply valve be capable of easy and ready actuation and that also the sand-delivery pipe or chute from 20 the sand-supply valve to the rails be clear and free of any obstructions to the passage of sand therethrough. Frequently the free and quick flow of sand to the rails has been prevented in track-sanding apparatus as 25 heretofore generally constructed, so far as I am aware, due to wet or damp sand accumulating and packing in, and thereby clogging up or choking, the sand-delivery pipe or chute.

30 With this premise, I may say that the principal object of my present invention is to provide an efficient track-sanding apparatus of comparatively simple form and construction having a normally closed sand-supply valve capable of being pneumatically actuated to open position and means 35 for directing a blast or flow of compressed air or other fluid under pressure into and through the sand-delivery pipe or chute, for 40 the purpose of clearing the same of sand which may have accumulated therein or of sand which may remain, and have a tendency to accumulate, therein, and hence obstruct the passage of sand therethrough, 45 both in advance of the opening of the sand-supply valve and following the closing of the same.

With the above and other objects in view, my invention resides in certain novel features of form, construction, arrangement, and combination of parts, all as will hereininafter be described and afterward pointed out in the claims.

In the accompanying drawings, which

show the preferred embodiment of my invention, Figure 1 is an end view of a car equipped with a track-sanding apparatus embodying my invention; Fig. 2 is an enlarged longitudinal sectional view of the compressed air supply or controlling valve 55 and its casing, the valve being shown in its normal or closed position; Fig. 3 is a similar view, the valve being shown in an intermediate or partly open position; Fig. 4 is also a similar view, the valve being shown in its abnormal or fully open position; Fig. 5 is an enlarged longitudinal sectional view of the sand-hopper throat or chute and its immediately associated parts, the sand-supply valve being shown in full lines in closed position and in dotted lines in open position; 60 and Fig. 6 is a detail transverse sectional view on approximately the line 6—6, Fig. 5.

Referring to the said drawings, in which like reference characters refer to like parts throughout the several views, 1 indicates a sand-box or receptacle of any suitable form and construction operatively arranged upon a car C at any suitable point—preferably at the front thereof. Preferably forming part 65 of, and leading downwardly from, sand-box 1 is an inverted cone-shaped portion or sand-hopper 2 having threaded or otherwise secured thereto a downwardly-disposed throat-portion or sand-chute A adapted, 70 either directly or through a short pipe-extension 3, to lead the delivered or supplied sand to and upon the track or rail 4. Preferably, to reduce manufacturing costs and 75 also in order that needed or necessary repairs or the like may be conveniently and readily made, sand-chute A is constructed or formed in two parts, namely, an upper member 5 and a lower member 6, suitably 80 detachably connected as by means of bolts 85 or the like 7, chute-members 5 and 6 being provided with outwardly-projecting registering ears 8—8 and 9—9, respectively, to receive the bolts 7, as clearly seen in Fig. 5.

Pivotaly swingable in sand-chute A at 100 the upper end of its lower member 6, is what might be called an unbalanced butter-fly valve adapted to control the supply of sand, this valve comprising a disk 10 to which is eccentrically fixed an axle or trunnions 105 11 extending transversely, and loosely arranged for rotatory movement in the wall, of chute A. At one side, the wall of chute

5 A at the base of its upper member 5 is inferiorly for approximately half its circumference arcuately cut away, as at 12, to permit ready swingable movement of valve-disk 10, the exposed portion of the upper face of lower chute-member 6 providing an approximately semi-circular shoulder, as at 13, adapted to limit the movement of valve-disk 10 to closing position and upon which 10 valve-disk 10 at its larger portion *a* is adapted to rest when in its normal or closed position. Suitably formed or provided on the inner face of the wall of lower chute-member 6 is an abutment or the like 14 adapted 15 to limit the pivotal movement of valve-disk 10 when pneumatically actuated, as herein-after appearing, to open position. Normally, under the overbalancing weight of its larger portion or part *a*, valve-disk 10 20 will automatically swingably seat itself to extend transversely across the bore of chute A and prevent the passage of sand therethrough. At its side opposite said cut-away portion 12, upper chute-member 5 is preferably integrally provided longitudinally 25 from adjacent its upper end to the lower end or base thereof with a thickened portion comprising external and internal bosses 15 and 16, respectively, for purposes hereinafter appearing, outer or external boss 15 being preferably rounded on its outer face, as indicated in Fig. 6. Lower chute-member 6 is similarly provided at its upper end with an outwardly-presented enlargement 30 or boss 17 forming an extension or continuation of external boss 15 of upper chute-member 5, as seen in Fig. 5. Below said enlargement or boss 17, lower chute-member 6 has preferably the form of an inverted cone to provide the chute longitudinally with a centrally-disposed contracted 35 outlet or mouth, as at 18.

40 Inner or internal boss 16 of upper chute-member 5 at its base is approximately segmental in form in inverted plan view, as seen in Fig. 6, and preferably has an area somewhat less than half (approximately three-sevenths) of the inner area of chute-member 5, the normal bore of chute-member 5 being correspondingly reduced or contracted immediately in advance of valve-disk 10 and the greater part of the sand entering chute A from hopper 2 being adapted 45 normally to bear upon portion *a* of valve-disk 10 and thereby hold valve-disk 10 to its seat in closed position. From its upper end to adjacent the base thereof, inner boss 16 has an obliquely inwardly and downwardly disposed face, as at 19, so that sand 50 entering chute or throat A may freely slide thereupon into the contracted or reduced lower or outlet portion of upper chute-member 5.

55 Suitably arranged preferably at the front 60 of the car convenient to the motorman or

operator thereof, is an elongated tubular valve-casing 20, in which is operatively mounted to move longitudinally relatively thereto what might be called a double-acting slide-valve adapted to control the compressed air or other fluid under pressure supply, this latter valve comprising a longitudinally-disposed plunger or stem 21 having fixed thereto within casing 20 a plurality of transversely disposed spaced-apart 70 disks 22, 23, and 24 having at their periphery an air-tight fit with the wall of casing 20 and providing within casing 20 air-chambers *c*, *d*, and *e*. Threaded into and closing the lower end of casing 20 is a nut or cap 80 25 having a cup-shaped portion 26 adapted to provide a seat for one end of a coiled spring 27 adapted to yieldingly maintain said slide-valve in its normally-closed or air-cutting off position, spring 27 at its other 85 or upper end having engagement with the under face of lowermost valve-disk 24. At its upper or projecting end, valve-stem 21 is provided with a head or enlargement 28, valve-stem 21 with its said disks having a 90 limited longitudinal movement relatively to casing 20 and being manually or otherwise depressible against the tension of spring 27.

95 Fixed to, or forming part of, valve-casing 20, is an air-chamber 29 in open communication through a pipe or air-passage 30 with a suitable source of compressed air or other fluid under pressure supply, such as, for instance, a reservoir or tank 31 carried by the car, a transverse opening or passage, as at 32, in the wall of casing 20 providing normally open means of communication between chamber 29 and the interior of casing 20. This opening or passage 32, as shown particularly in Fig. 2, is so located 100 relatively to the disks of said slide-valve that, when said valve is, under the tension of spring 27, in its normal or closed position, the upper face of lowermost disk 24 is preferably approximately slightly below 105 the plane thereof, intermediate chamber *d* being consequently, as shown, also normally in open communication with chamber 29 and hence also with said source of fluid supply, but communication between said chamber 29 and valve-casing chambers *c* and *e* being cut-off by intermediate and lowermost disks 23 and 24, respectively. 110

115 Leading at one end from casing 20 and having its entrance-opening slightly above 120 the plane of the upper face of intermediate valve-disk 23 when said valve is in its normal or closed position, as clearly seen in Fig. 2, is an air-pipe or passage 33 communicating at its other end with an air-passage 34 bored or otherwise provided in said thickened portion of upper chute-member 5, this air-passage 34, which is substantially a continuation or extension of air-pipe or passage 33, extending in said thick- 125

- ened portion of chute-member 5 obliquely inwardly and downwardly into and through inner boss 16 and discharging on the under face thereof at a point directly above 5 smaller portion *b* of valve-disk 10, whereby, on compressed air or other fluid under pressure flowing from said source of supply into said air-passage 33 and its continuation 34, the same will, on discharging therefrom directly upon said valve-disk portion *b*, pneumatically swingably actuate valve-disk 10 against the weight of sand thereupon into open position, or into the position thereof shown in dotted lines in Fig. 5, to permit 10 sand from hopper 2 to pass through lower chute-member 6 on to the rail 4, the continued supply of compressed air or other fluid under pressure so directed from air-passage 34 upon valve-disk 10 not only 15 pneumatically maintaining said disk in open position, but also carrying the delivered sand therewith through lower chute-member 6 and its mouth 18 to the exterior. Also leading at one end from casing 20 and having 20 its entrance-opening slightly below the plane of the under face of lowermost valve-disk 24 when said slide-valve is in its normal or closed position, as also clearly seen in Fig. 2, is an air-pipe or passage 35 communicating at its other end with an air-passage 36 bored or otherwise provided in 25 said boss 15 and its continuation 17, this air-passage 36, which is likewise substantially an extension of air-pipe or passage 35, 30 discharging directly into lower chute-member 6 at a point preferably some little distance below the upper end thereof and hence also below said valve-disk 10, as shown in Fig. 5.
- 35 In operation or use, on valve-stem 21 being depressed or actuated inwardly relatively to casing 20, lowermost disk 24 will be first carried past the entrance-opening of air-passage 35, when, through casing- 40 chamber *d* and port or opening 32, communication will be at once established, as seen in Fig. 3, between air-passage 35 and the source of compressed air supply, the compressed air or other fluid under pressure so supplied to air-passage 35 discharging into chute-member 6 and on its way to the exterior driving from said chute-member and its outlet or mouth 18 any sand which may have accumulated or otherwise lodged therein, thereby providing a clear channel or passage to the exterior for the sand soon to be delivered from hopper 2. Communication between air-passage 35 and the source of compressed air supply remains open and compressed air continues to flow through air-passage 35 into lower chute-member 6 until, on further depression of valve-stem 21, intermediate disk 23 is carried past or below entrance-port 32, when communication between the source of supply and said 45
- air-passage 35 will be at once cut off and opened or established between the source of supply and said air-passage 33, as shown in Fig. 4, the compressed air from the source of supply now flowing therefrom into and through air-passage 33 and its continuation 34 and actuating said valve-disk 10 to, and maintaining said disk in, open position, as hereinbefore described. On valve-stem 21 being released and returning, under the tension of spring 27, to normal or closed position, communication between the source of compressed air supply and air-passage 33 will first be cut-off, valve-disk 10 then returning to, or assuming, its normal closed position, and communication again, for a short interval, established between the source of compressed air supply and air-passage 35, a second blast of compressed air being delivered into lower chute-member 50 to clear the same of any sand or the like remaining therein, communication between the source of supply and air-passage 35 being again cut off on valve-stem 21 with its said disks reaching normal position. 55
- 50 By my new track-sanding apparatus, as will be seen from the foregoing, I not only provide a sand-supply valve capable of being conveniently and readily pneumatically actuated to, and maintained in, open position by the motorman or operator of the car to deliver sand to the rails when and as required, but am also enabled to deliver air-blasts into the throat or chute of the sand-hopper, both in advance of, and following, the charge of delivered sand, to provide a clear and unimpeded passage for the same to the rails. My new track-sanding apparatus, in all its several parts, may be economically manufactured and also 55 readily installed on a car, and while my new sanding-apparatus is especially designed for street or electric-car service, yet it is to be understood that it is equally well adapted for steam railway use. 60
- 65 I am aware that changes in the form, construction, arrangement, and combination of the several parts of my new track-sanding apparatus may be made and substituted for those herein shown and described without departing from the nature and principle of my invention.
- 70 Having thus described my invention, what I claim and desire to secure by Letters Patent is:
- 75 1. In a track-sanding apparatus, the combination with a sand-hopper, of a disk swingable in, and normally closing, the throat of said hopper, and means for pneumatically swinging said disk to open position; substantially as described. 80
- 85 2. In a track-sanding apparatus, the combination with a sand-hopper, of an unbalanced disk pivotally swingable in, and normally closing, the throat of said hopper, and 85

means for pneumatically pivotally swinging said disk to open position; substantially as described.

3. In a track-sanding apparatus, the combination with a sand-hopper, of an unbalanced disk pivotally swingable in, and normally closing, the throat of said hopper, and means for pneumatically pivotally swinging said disk to open position, said means including an air-passage discharging upon the smaller part of said disk, and a valve for controlling the supply of fluid under pressure to said air-passage; substantially as described.

4. In a track-sanding apparatus, the combination with a sand-hopper, of an unbalanced disk pivotally swingable in, and normally closing, the throat of said hopper, an internal enlargement in the throat of said hopper above and covering the smaller part of said disk, and means for pneumatically pivotally swinging said disk to open position, said means including a valve-controlled air-passage extending through said enlargement and arranged to discharge obliquely upon the smaller part of said disk; substantially as described.

5. In a track-sanding apparatus, the combination with a sand-hopper, of a pneumatically operated valve normally closing the throat of said hopper, means for pneumatically operating said valve to open position, and means for supplying a blast of compressed air to the throat of said hopper beyond, and in advance of the opening of, said valve; substantially as described.

6. In a track-sanding apparatus, the combination with a sand-hopper, of a pneumatically operated valve normally closing the throat of said hopper, means for pneumatically operating said valve to open position, and means for supplying a blast of compressed air to the throat of said hopper beyond, and following the closing of, said valve; substantially as described.

7. In a track-sanding apparatus, the combination with a sand-hopper, of a pneumatically operated valve normally closing the throat of said hopper, means for pneumatically operating said valve to open position, and means for supplying blasts of compressed air to the throat of said hopper beyond, and both in advance of the opening and following the closing of, said valve; substantially as described.

8. In a track-sanding apparatus, the combination with a sand-hopper, of a pneumatically operated valve normally closing the throat of said hopper, and means for pneumatically operating said valve to open position and for supplying blasts of compressed air to the throat of said hopper beyond, and both in advance of the opening and following the closing of, said valve; substantially as described.

9. In a track-sanding apparatus, the combination with a sand-hopper, of a disk swingable in, and normally closing, the throat of said hopper, and means for pneumatically swinging said disk to open position and for supplying blasts of compressed air to the throat of said hopper beyond, and both in advance of the opening and following the closing of, said disk; substantially as described.

10. In a track-sanding apparatus, the combination with a sand-hopper, of an unbalanced disk pivotally swingable in, and normally closing, the throat of said hopper, and means for pneumatically swinging said disk to open position and for supplying blasts of compressed air to the throat of said hopper beyond, and both in advance of the opening and following the closing of, said disk, said means including an air-pipe discharging into the throat of said hopper upon the smaller part of said disk, a second air-pipe discharging into the throat of said hopper beyond said disk, and a valve for controlling the supply of compressed air in turn to each of said air-pipes; substantially as described.

11. In a track-sanding apparatus, the combination with a sand-hopper, of an unbalanced disk pivotally swingable in, and normally closing, the throat of said hopper, a valve-casing, said casing being normally in open communication with a source of compressed air supply, an air-pipe from said casing discharging into the throat of said hopper upon the smaller part of said disk, a second air-pipe from said casing discharging into the throat of said hopper beyond said disk, and a valve movable in said casing adapted to open and close communication in turn through said casing between said source of supply and said air-pipes; substantially as described.

12. In a track-sanding apparatus, the combination with a sand-hopper, of an unbalanced disk pivotally swingable in, and normally closing, the throat of said hopper, a valve-casing, said casing being normally in open communication with a source of compressed air supply, an air-pipe from said casing discharging into the throat of said hopper upon the smaller part of said disk, a second air-pipe from said casing discharging into the throat of said hopper beyond said disk, and a spring-pressed valve in said casing adapted to open and close communication through said casing in turn between said source of supply and said air-pipes, said valve including a stem longitudinally movable relatively to said casing, and a plurality of spaced-apart disks transversely disposed within said casing fixed to, and movable with, said stem; substantially as described.

13. In a track-sanding apparatus, the

combination with a sand-hopper, the throat of said hopper being provided with an internal boss reducing the normal bore thereof, of an unbalanced disk pivotally swingable in, and normally closing, the throat of said hopper, said disk when in normal position having its smaller portion disposed flatwise directly beneath said boss, and means for actuating said disk to open position; substantially as described.

14. In a track-sanding apparatus, the combination with a sand-hopper, of a valve in the throat of said hopper adapted to open and close the same, and a valve-controlled air-pipe discharging into the throat of said hopper beyond said valve; substantially as described.

15. In a track-sanding apparatus, the combination with a sand-hopper, of means for delivering charges of compressed air successively, and at different points in, the throat of said hopper; substantially as described.

16. In a track-sanding apparatus, the combination with a sand-hopper, of means for delivering a charge of compressed air into, and at a certain point in, the throat of said hopper and for delivering another charge of compressed air into, and at a different point in, the throat of said hopper in advance, and prior to the delivery, of said first charge; substantially as described.

17. In a track-sanding apparatus, the combination with a sand-hopper, of means for delivering a charge of compressed air into, and at a certain point in, the throat of said hopper and for delivering another charge of compressed air into, and at a different point in, the throat of said hopper following, and subsequent to, said first charge; substantially as described.

18. In a track-sanding apparatus, the combination with a sand-hopper, of means for delivering a charge of compressed air into, and at a certain point in, the throat of said hopper and for delivering other charges of compressed air into, and at a different point in, the throat of said hopper, respectively, in advance of, and following, said first charge; substantially as described.

19. In a track-sanding apparatus, the combination with a sand-hopper, of an air-delivery pipe leading into the throat of said hopper and discharging at a certain point

therein, a second air-delivery pipe leading 55 into the throat of said hopper and discharging at a different point therein, and means for controlling admission of compressed air into said pipes successively; substantially as described.

20. In a track-sanding apparatus, the combination with a sand-hopper, of an air-delivery pipe leading into, and discharging at a certain point in, the throat of said hopper, a second air-delivery pipe leading 65 into, and discharging at a different point in, the throat of said hopper, and means for controlling admission of compressed air first into said second pipe, then into said first pipe, and then again into said second pipe; 70 substantially as described.

21. In a track-sanding apparatus, the combination with a sand-hopper, of an air-delivery pipe leading into, and discharging at a certain point in, the throat of said hopper, a second air-delivery pipe leading 75 into, and discharging at a different point in, the throat of said hopper, and means for controlling admission of compressed air first into said second pipe, then into said first 80 pipe, and then again into said second pipe, said means including a valve adapted for manual manipulation to successively open and close the entrance-openings of said pipes; substantially as described.

22. In a track-sanding apparatus, the combination with a sand-hopper, of a valve-casing normally in communication with a source of compressed air supply, an air-pipe leading from said casing into, and discharging at a certain point in, the throat of said hopper, a second air-pipe leading from said casing into, and discharging at a different point in, the throat of said hopper, a stem lengthwise movable in said casing, 95 and a plurality of spaced-apart members on said stem within said casing adapted to successively open and close the entrance-openings of said pipes; substantially as described.

In testimony whereof, I have signed my name to this specification, in the presence of two subscribing witnesses.

ALBERT H. CARNES.
